VENETIAN BLIND

Louis J. Znidarsic, Euclid, Ohio

Application April 11, 1950, Serial No. 155,263

8 Claims. (Cl. 160—173)

1

This invention relates to improvements in Venetian blinds generally made up of a top tilt bar, a bottom drop bar, a ladder like webbing, including cross strips, secured between the bars to support intermediate slats and tilting and elevator cords.

The common practice in actual usage is to secure the webbing to the drop bar by such means as tacks. Many difficulties arise from such practice, such as lack of means of adjustment for insuring parallelism between the slats throughout the arc of their tilting movements and lack of ready detachability of the cords, webs and slats for cleaning, painting and reinstallation or replacement.

An object of this invention is to provide a simple, practical, economical and neat appearing quick detachable means for adjustably securing the webs and elevator cords to the drop bar, so that the webs, slats, cords and drop bar may be all, or separately, removed for cleaning, repairing, painting, or replacement, or so that the cords may be removed, leaving the webs and their cross strips secured in place for supporting the slats, which latter may be separately removed, one at a time for any desired purpose.

Another object is to provide such an attachment device that is not dependent upon dependable spring or hinge elements, that includes positively acting opposing means for quick detachable securing of the drop bar, web and elevator cord together and which requires no tools for assembly or disassembly.

Another object is to provide a simple means for elevator cord attachment that not only eliminates the necessity of threading the cord end, but which also serves as a guard therefor.

With the foregoing and other objects in view, the invention resides in the combination of parts and details of construction hereinafter set forth in the following specification and appended claims, certain embodiments thereof being illustrated in the accompanying drawings, in which:

Figure 1 is a view in transverse section taken through the drop bar, showing the cord retaining housing partly in elevation and partly in section;

Figure 2 is a view in section taken along line 2—2 of Figure 1;

Figure 3 is an exploded view in perspective of the component parts of the attachment device; and

Figure 4 is a bottom plan view of a portion of the drop bar showing the web and elevator cord secured to the bar by the attachment device, and showing the retaining guard partially removed to show the elevator cord end folded in place.

2

Referring more particularly to the drawings, it is to be borne in mind that I am addressing myself to improvements in quick detachable means for adjustably securing the webs and elevator cords to the drop bar of an otherwise conventional Venetian blind construction having a top cord operated tilt bar, a pair, or more, of sets of parallel webs, of the ladder type, secured to the top tilt bar and bottom drop bar, and having a series of spaced cross strips to support a series of parallel slats, and also an elevator cord secured to the drop bar and extending over a top pulley for manual control.

In the drawings are shown a drop bar 1, an elevator cord 2 and one pair of slat supporting webs 3 and 4. The drop bar is provided with a cylindrical hole 5 extending through its vertical length. The attachment device also includes a hollow frustro-conical sleeve 6 and top flange 9 of lesser outside diameter than cylindrical hole 5 and an integral plate 7 of considerably greater proportions than hole 5. Plate 7 also has a central hole 8 to register with hole 5. Releasably secured to plate 7 is a plastic cover 10 with a central hole 11. The means of securing the plate and cover may comprise a plurality of edge notches 12 in cover 10 and a like number of malleable prongs 13 on the edges of plate 7 to be bent over into notches 12. Cover 10 has its upper central longitudinal length, as viewed in Figure 3, recessed to form a slot 14 between cover 10 and plate 7.

Removably but snugly fitting in the sleeve 6 is a plastic frustro-conical plug 15. This plug has a side groove 16 and a bottom end groove 17 in its larger end.

With the parts described, one preferred method of assembly to secure the parts together to properly secure the webs and cord is as follows: The sleeve 6 is thrust upwardly through hole 5 in the bar until its upper flange 9 extends beyond the top of bar 1. The lower end portion of the elevator cord 2 is then laid in the open side groove 16 and folded over into the open end groove 17 of plug 15. The plug 15 is then forced upwardly into hole 8 of sleeve 6. The depth of open groove 16 is less than the diameter of the elevator cord so that there is a snug engagement of the plug and cord with the sleeve 6 and the surface of groove 16 may be roughened to assist the snug engagement of the cord. Thus, an upward pull on the cord only serves to tighten this snug engagement and effectively guards against slippage of the cord.

The lower ends of the two parallel side webs are then placed to overlap a desired portion of the under surface of the drop bar 1. Then plate

7, with its cover 10, is forced upwardly so that its two sets of side edge teeth 18 engage the corresponding webs 3 and 4. The next step is to force a spring clip 19 so that its two legs 20 and 21 straddle the sleeve 6 under its top flange 9. This resiliently retains the assembly in place and securely grips the web ends to the drop bar. The clip 19 is provided with an upturned end flange 22 for ease of hand engagement for insertion and removal of the clip.

This leaves the bottom end of the elevator cord bare. The next step in the final assembly is to lay the exposed folded end 2' of the cord 2 in the bottom open groove 17 of plug 15. Then, a spring clip 23, similar to spring clip 19, is placed in the slot 14 between the upper surface of cover 10 and the lower surface of plate 7, as shown in Figure 4, in which the bottom end of plug 15 and the folded end 2' of cord 2 are shown exposed. The clip 23 is then pushed inwardly, or from right to left as viewed in Figure 4, which effects a covering of the hole 11 of cover 10 and also of the plug and the cord. The clip 23, like clip 19, is provided with a flange 24 for convenience in manual handling.

As will readily be seen, the device is simple in construction and assembly. There is no threading of the cord involved, which, when the cord end becomes frayed or unraveled, could become very difficult and bothersome. The cord is merely laid sidewise in the side groove 16 of plug 15 and when the plug is inserted in sleeve 6 an effective gripping of the cord against slippage is obtained. Pulling of the cord only tightens the grip. The effective length of the cord is determined by the amount of overlap 2' and the removable clip 24 protects it against damage. As the engagement of plug 15 in sleeve 6 locks the cord, the engagement of spring clip 19 under flange 9 of sleeve 6 locks the webs in place. The amount of overlap of the web edges under the drop bar to be engaged by teeth 18 of plate 7 determines the effective length of the webs. Thus the degree of adjustment of the webs is unlimited. The essential locking elements consist in the plug and its engagement with sleeve 6 to lock the cord and the engagement of clip 19 with flange 9 of sleeve 6 to bring the teeth of plate 7 into engagement with the webs to lock them.

The locking action involves no spring hinges nor threading of the cord. Disassembly is just as simple. It is only necessary to remove clip 19 to remove the webs and it is only necessary to remove clip 23 to gain access to the cord end 2'. A slight pull on the lower folded end portion 2' of the elevator cord causes the plug 15 to drop out of sleeve 6 so that the elevator cord is no longer gripped. This gives access to the removal of the elevator cord and the slats, through which slats the elevator cords normally extend when the Venetian blind is assembled. As a further refinement, the bottom groove 17 and its side edges may be provided with a radius extending upwardly from the bottom edge away from the edge along the groove 16. The purpose of this radius is to accommodate frayed ends of the elevator cords so as to permit clip 23 to slide over it to cover it.

It will be seen that no tools are required for assembly or disassembly. Convenient hand manipulation of clips 19 and 23 by their flanges 22 and 24 is all that is required.

I claim:

1. In a Venetian blind of the type having an

upper tilt bar, a bottom drop bar, slats and ladder type parallel supporting webs therefor, a tilt cord and an elevator cord, the combination of a quick detachable means for adjustably securing said elevator cord to said drop bar, said means comprising a hollow sleeve extending through a vertical aperture in said drop bar, said sleeve having a relatively large bottom plate to engage said drop bar and a top flange insertable through said aperture, a slidable clip for engaging said top flange to secure said sleeve to said drop bar, a wedge plug insertable in said hollow sleeve and having an open side groove to flatwise receive a desired length of said elevator cord.

2. In a Venetian blind of the type having an upper tilt bar, a bottom drop bar, slats and ladder type parallel supporting webs therefor, a tilt cord and an elevator cord, the combination of a quick detachable means for adjustably securing said elevator cord to said drop bar, said means comprising a hollow sleeve extendable through a vertical aperture in said drop bar, said sleeve having a relatively large bottom plate to engage said drop bar and a top flange insertable through said aperture, a slidable clip for engaging said top flange to secure said sleeve to said drop bar, a wedge plug insertable in said hollow sleeve and having an open side groove to flatwise receive a desired length of said elevator cord, said wedge plug having an open bottom groove to receive the folded over end portion of said elevator cord.

3. In a Venetian blind of the type having an upper tilt bar, a bottom drop bar, slats and ladder type parallel supporting webs therefor, a tilt cord and an elevator cord, the combination of a quick detachable means for adjustably securing said elevator cord to said drop bar, said means comprising a hollow sleeve extendable through a vertical aperture in said drop bar, said sleeve having a relatively large bottom plate to engage said drop bar and a top flange insertable through said aperture, a slidable clip for engaging said top flange to secure said sleeve to said drop bar, a wedge plug insertable in said hollow sleeve and having an open side groove to flatwise receive a desired length of said elevator cord, said wedge plug having an open bottom groove to receive the folded over end portion of said elevator cord and a clip slidably mounted in said bottom plate for engaging and concealing the bottom end portion of said elevator cord.

4. In a Venetian blind of the type having an upper tilt bar, a bottom drop bar, slats and ladder type parallel supporting webs therefor, a tilt cord and an elevator cord, the combination of a quick detachable means for adjustably securing said webs to said drop bar, said means comprising a hollow sleeve extendable through a vertical aperture in said drop bar, said sleeve having a relatively large bottom plate to engage said drop bar and a top flange insertable through said aperture, a slidable clip for engaging said top flange to secure said sleeve to said drop bar, said bottom plate having upper edge teeth for gripping adjustable lengths of said parallel webs to grip the webs against the under surface of said drop bar between the positive action of said bottom plate and the engagement of said top clip with the top flange of said sleeve above the upper surface of said drop bar.

5. In a Venetian blind of the type having an upper tilt bar, a bottom drop bar, slats and ladder type parallel supporting webs therefor, a tilt cord and an elevator cord, the combination of a quick

detachable means for adjustably securing said elevator cord to said drop bar, a quick detachable means for adjustably securing said webs to said drop bar, said means comprising a hollow sleeve extendable through a vertical aperture in said drop bar, said sleeve having a relatively large bottom plate to engage said drop bar and a top flange insertable through said aperture, a slideable clip for engaging said top flange to secure said sleeve to said drop bar, said bottom plate having upper edge teeth for gripping adjustable lengths of said parallel webs to grip the webs against the under surface of said drop bar between the positive action of said bottom plate and the engagement of said top clip with the top flange of said sleeve above the upper surface of said drop bar.

6. In a Venetian blind of the type having an upper tilt bar, a bottom drop bar, slats and ladder type parallel supporting webs therefor, a tilt cord and an elevator cord, the combination of a quick detachable means for adjustably securing said elevator cord to said drop bar, a quick detachable means for adjustably securing said webs to said drop bar, said means comprising a hollow sleeve extendable through a vertical aperture in said drop bar, said sleeve having a relatively large bottom plate to engage said drop bar and a top flange insertable through said aperture, a slideable clip for engaging said top flange to secure said sleeve to said drop bar, a wedge plug insertable in said hollow sleeve and having an open side groove to flatwise receive a desired length of said elevator cord, said bottom plate having upper edge teeth for gripping adjustable lengths of said parallel webs to grip the webs against the under surface of said drop bar between the positive action of said bottom plate and the engagement of said top clip with the top flange of said sleeve above the upper surface of said drop bar.

7. In a Venetian blind of the type having an upper tilt bar, a bottom drop bar, slats and ladder type parallel supporting webs therefor, a tilt cord and an elevator cord, the combination of a quick detachable means for adjustably securing said elevator cord to said drop bar, a quick detachable means for adjustably securing said webs to said drop bar, said means comprising a hollow sleeve extendable through a vertical aperture in said drop bar, said sleeve having a relatively large bottom plate to engage said drop bar and a top flange insertable through said aperture, a slideable clip for engaging said top flange to secure said sleeve to said drop bar, a wedge plug insertable in said hollow sleeve and having an open side groove to flatwise receive a desired length of said

elevator cord, said wedge plug having an open bottom groove to receive the folded over end portion of said elevator cord, said bottom plate having upper edge teeth for gripping adjustable lengths of said parallel webs to grip the webs against the under surface of said drop bar between the positive action of said bottom plate and the engagement of said top clip with the top flange of said sleeve above the upper surface of said drop bar.

5 8. In a Venetian blind of the type having an upper tilt bar, a bottom drop bar, slats and ladder type parallel supporting webs therefor, a tilt cord and an elevator cord, the combination of a quick 15 detachable means for adjustably securing said elevator cord to said drop bar, a quick detachable means for adjustably securing said webs to said drop bar, said means comprising a hollow sleeve extendable through a vertical aperture in said drop bar, said sleeve having a relatively large bottom plate to engage said drop bar and a top flange insertable through said aperture, a slideable clip for engaging said top flange to secure said sleeve to said drop bar, a wedge plug insertable 20 in said hollow sleeve and having an open side groove to flatwise receive a desired length of said elevator cord, said wedge plug having an open bottom groove to receive the folded over end portion of said elevator cord, a clip slidably 25 mounted in said bottom plate for engaging and concealing the bottom end portion of said elevator cord, said bottom plate having upper teeth for gripping adjustable lengths of said parallel webs to grip the webs against the under surface 30 of said drop bar between the positive action of said bottom plate and the engagement of said top clip with the top flange of said sleeve above the upper surface of said drop bar.
